FOREIGN PATENT DOCUMENTS

JP 1528731 * 7/2015

Primary Examiner — Messina L Smith
 Assistant Examiner — Carolyn W Davis

(57) **CLAIM**

The ornamental design for an air purifier, as shown and described.

DESCRIPTION

FIG. 1 is a front, top perspective view of an air purifier, showing our new design;
 FIG. 2 is a rear, bottom perspective view thereof;
 FIG. 3 is a front elevation view thereof;
 FIG. 4 is a rear elevation view thereof;
 FIG. 5 is a left side elevation view thereof;
 FIG. 6 is a right side elevation view thereof;
 FIG. 7 is a top plan view thereof; and,
 FIG. 8 is a bottom plan view thereof.

The broken lines in the figures illustrate portions of the air purifier that form no part of the claimed design.

1 Claim, 8 Drawing Sheets(56)
